(57) **CLAIM**

The ornamental design for a portion of furniture, as shown and described.

DESCRIPTION

FIG. 1 is a perspective view of a portion of furniture showing my new design.

FIG. 2 is a top planar view of the portion of furniture of FIG. 1.

FIG. 3 is a front elevational view of the portion of furniture of FIGS. 1 and 2; and,

FIG. 4 is a rear elevational view of the portion of furniture of FIGS. 1 to 3.

The broken lines in the figures are for illustrative purposes only and form no part of the claimed design.
